UNITED STATES PATENT OFFICE.

ARSENE SAULNIER, OF WALTHAM, MASSACHUSETTS.

CLOCK FOR WARPING MACHINES.

Application filed January 25, 1921. Serial No. 439,777.

To all whom it may concern:

Be it known that I, ARSENE SAULNIER, a citizen of the United States, residing at Waltham, in the county of Middlesex, State 5 of Massachusetts, have invented a certain new and useful Improvement in Clocks for Warping Machines, of which the following is a specification, reference being had thereto in the accompanying drawings.

10 The invention has relation to the so-called clocks which are employed in warping and other machines for the purpose of registering the length of assembled threads which passes through a machine, and of bringing 15 about the stopping of the machine when a predetermined measured length has passed. It further has relation to clocks on the order of what are termed lease-clocks, these being contrived to cause stoppage of the machine at intermediate points during the passage 20 of the total predetermined length of assembled threads, for the purpose of enabling lease-threads or cords to be introduced at predetermined intervals among the assembled threads.

25 The invention consists in novel locking means for the follower of a warper clock, and embodies the same general principles as the locking means of the same class that is 30 more broadly claimed in my application for U. S. Letters Patent for improvement in clocks for warping machines filed January 22, 1921, Serial No. 439,128.

35 In usual practice, the clock of a warping machine comprises a spirally-grooved barrel, called a scroll, and a follower engaging in the spiral groove of the scroll. The scroll is geared with a measuring roll which is rotated through the contact of the traveling 40 yarns with its periphery, and the follower is traversed to act in connection with other parts with which it is associated to indicate into action at the required time or times the stop motion mechanism of the machine. In 45 the case of some warping machines the clock brings about the stoppage of the machine only on the completion of the required total length of assembled threads. In the operation of a lease-warper the clock causes ar- 50 rest of the machine after a certain number of yards has passed through, whereupon the attendant introduces lease-threads or cords and restarts the machine, the stoppage, induction of lease-threads or cords, and re- 55 starting being repeated at intervals until the final automatic stoppage of the machine

which indicates the passage of the total predetermined length.

Trouble and loss are experienced often in practice in consequence of accidental displacement of the follower of a clock relative to the turns of the spiral of the clock scroll. Such displacement results in false registration by the clock, and in inaccurate measurement, involving for instance either 60 too many or an insufficient number of yards of threads being passed through the machine. Displacement is not detected readily, and usually passed unobserved so that the error is not discovered until later on in the 65 handling or use of the assembled threads.

70 What has just been stated will be more clearly apparent after reference to the practice in connection with beam warpers. A beam warper is employed to wind threads on 75 a beam, from spools mounted in a creel, until the required length of threads has been thus wound. The number of threads thereby wound upon the beam is a fractional part of the entire number of threads required to 80 make the contemplated warp, and constitutes one so-called section of the warp. In like manner as many sections are wound upon other beams as are necessary to make up the required total of the threads for the 85 said warp. All of the sections are combined at the slasher, and after passing all together through the later are wound upon a single beam in readiness to be placed in a loom. Obviously all the sections of a warp should 90 be of the same length. If one or more sections, through error in the winding thereof upon the corresponding section beam or beams, should be either shorter or longer than the others, loss or trouble would 95 result. The excess of length in the case of the longer section or sections of a warp would become waste.

100 The purpose of the subject-matter of the present invention is to prevent displacement of the follower.

An illustrative embodiment of the invention is shown in the accompanying drawings, in which,—

105 Fig. 1 is an elevation of a warper-clock of a form in general use at the present time, together with a portion of a warper-frame in vertical section, and a portion of the measuring roll of such machine.

Fig. 2 is a side elevation of the parts that 110 are shown in Fig. 1.

Fig. 3 is a plan view of the said parts.

Having reference to the drawings,—

One side-frame of a warping machine is shown at 1 (partly). The measuring and registering devices shown in the drawings 5 include the measuring roll 2, which, as usual, is rotated through the contact of the traveling yarns with its periphery, the spirally-grooved scroll 10, and motion-transmitting connections by which the rotation 10 of the measuring roll 2 serves to cause the scroll to rotate. The said connections comprise in this instance the worm 4 on one journal, 3, of the measuring roll, the worm-wheel 5 engaged by the said worm, the 15 worm 6 on the shaft 7 of the said worm-wheel 5, and the worm-wheel 8 fast with the scroll 10. The shaft 7 and the scroll 10 are suitably mounted in connection with the upright portion 11 of the clock-frame, 20 the latter being attached to the side-frame 1 of the warper. The particular form of warper-clock that is shown in the drawings is what is termed a lease-clock, the scroll 10 being provided with a series of longitudinal 25 lease-grooves 10^a, 10^a, in addition to the final stopping notch 10^b at the end of the scroll. The lease-grooves extend longitudinally of the body of the scroll and intersect the otherwise continuous spiral groove 30 of the scroll, as usual. The follower-arm 11 is provided with a projection 11^a, Fig. 2, working in the spiral groove of the scroll 10 and adapted to drop into the longitudinal lease-grooves 10^a, 10^a, and into the final 35 stopping notch 10^b as the respective lease-grooves and the said stopping notch successively are presented to the said projection 11^a by the rotation of the scroll. The said follower-arm is hung upon the shaft *a* extending from the side-frame 1 parallel with 40 the scroll-axis and is adapted to slide along the said shaft in being traversed by the action of the scroll as the latter turns. The projection 11^a of the follower is kept down 45 against the bottom of the spiral groove of the scroll by the weight of the main arm of the follower. The groove-bottom sustains the follower so as to keep the latter normally turned into a position in which the 50 tripping-finger 11^b is clear of the co-acting stop-motion devices (not shown) so as not to interfere with the running of the machine. Each time during the rotation of the scroll a lease-groove 10^a (each of which is deeper 55 than the scroll-groove) is presented in position to receive the projection 11^a, the follower drops as in Fig. 2, so as to cause the trip-arm or finger 11^b to be moved into position to bring about unshipping of the driving power and the stopping of the machine 60 for the insertion of lease-threads or cords. So, also, when the follower has been traversed out to the outer end of the scroll and the final stopping notch 10^b is presented in 65 position to receive the projection 11^a of the

follower, the follower drops and the trip-finger becomes operative to bring about the stoppage at the conclusion of the required total number of yards of threads passed through the machine.

In the case of warper-clocks not equipped with follower-locks it happens often that the follower is disengaged from the scroll-thread or groove, either accidentally or thoughtlessly, and either is not at once restored to engagement, or in being reengaged does not become engaged in or with the same turn from which it was withdrawn. Accidental disengagement may occur as a result of an attendant, in working around a warper, as when occupied with the cleaning thereof, hitting or pushing against the follower. Other disengagements result sometimes through absent-minded or thoughtless lifting of the follower, and sometimes are due to casual meddling by persons passing by or observing the operation of the mechanism. If, while the machine is in operation, with yarns passing therethrough, the follower is disengaged from the scroll and not instantly restored to engagement with the same turn of groove or thread, at the identical point of such turn from which it was taken, the registering function of the clock will be interfered with and the final stoppage will not correspond with the passage of the correct number of yards of threads. Even though the follower is restored with comparative promptness to engagement with the same turn, the total length that will have passed through the machine up to the time of final stoppage through the entrance of the follower into the notch 10^b will exceed the correct length by the number of yards that pass between the instant of withdrawal of the follower and the instant of its reengagement. An excess of inconvenient amount occurs in cases in which the follower, after being disengaged, lands upon the rib between the turn last occupied by it and one of the adjoining turns, and remains supported upon such rib for a while before dropping back into the former turn. The exact length that has passed through the machine is not obvious upon inspection of the wound mass of threads, and can only be approximated by weighing such mass. Consequently, errors in length frequently pass unobserved for the time being; when suspected or known, the extent thereof is not easy of ascertainment and usually accuracy in the correction thereof is difficult of accomplishment. If the follower, after having been lifted, drops into an adjoining turn either preceding or following the turn from which it was lifted, and either directly in being returned toward working relations or after first having landed upon the intermediate rib, the total length passed through the machine up to the final 130

stoppage may be greatly in excess or greatly below the required length. Just how much, can be ascertained only by weighing what has passed through; the extent of the error 5 cannot be determined merely from looking at the scroll and follower.

Referring now more particularly to the features of the illustrative embodiment of the invention:

10 The precise constructional form of the said features adopted in practice, and the precise arrangement, etc., of the parts, may vary more or less according to requirements, and will be governed by the construction 15 and specific mode of operation, etc., of the warper-clock or of the warper itself, and by the views and requirements of builders and users of the mechanism.

In the case of warper-clocks as usually 20 constructed, the place of the shaft *a* in the said illustrative embodiment is taken by a simple stud projecting from the side-frame of the warper, on which stud the hub 11^c of the follower is adapted to turn independently in addition to sliding lengthwise of 25 the stud. As a feature of the present invention I connect or engage the said hub with shaft *a* in a manner which while leaving the follower free to be moved along the 30 shaft connects or engages the follower and shaft with each other in such manner as to cause them to turn in unison. In this instance a longitudinal groove *a'* is formed in the shaft *a*, and the inner end of a screw 35 11^d applied to the hub 11^c enters the said groove. Thereby in effect the follower is splined to the shaft. The latter is mounted in a bearing at *a*² in connection with side-frame 1 so as to be capable of turning 40 around its longitudinal axis. The locking means by which the follower is locked from being rocked in the manner that is required in order to permit it to be disengaged from the scroll-groove is arranged for direct co- 45 operation with the shaft *a*. In this instance it comprises essentially two members arranged and constructed for interengagement, one of them being a fixed member in connection with the machine-frame, and the 50 other being attached to the shaft *a*. Herein the fixed member is a pin *b* projecting from the bearing *a*² in an outward direction parallel with the shaft *a*, and the second member is a collar *c* fast upon the shaft *a* 55 and formed with a peripheral notch *c'* into which the said stud enters. So long as the notch *c'* is occupied by the stud or pin *b* the shaft and consequently the follower are locked from turning so as to prevent there- 60 by the follower from being raised far enough to disengage its projection 11^a from the scroll-groove. In order to enable the follower to be unlocked by the attendant whenever necessary, I provide for disen- 65 gaging the locking members *b* and *c* from

each other by rendering the shaft *a* movable in the direction of its length. To this end the shaft *a* is mounted in the bearing *a*² with capacity for endwise movement, so that the attendant by taking hold of the same 70 by hand may move it outward lengthwise and thereby effect the disengagement, the subsequent lengthwise movement of the shaft inward having the effect of causing the locking members *b* and *c* to become re- 75 engaged with each other. For the purpose of holding the members *b* and *c* normally in interlocking engagement I combine a spring *d* with the shaft *a* in such manner that the said spring tends to move the shaft 80 lengthwise in an inward direction. Thus, in this instance, the said spring is mounted upon a portion of the shaft which projects inwardly beyond the bearing *a*², the spring being confined between the end of the bearing 85 *a*² and a washer *e* that is held in place upon the inner extremity of the shaft by means of a cotter-pin *f*. The spring yields to permit the shaft to be pulled lengthwise outward for the purpose of effecting the un- 90 locking, and when the shaft is released the spring acts to pull the shaft lengthwise inward again to bring about the relocking.

By way of further precaution I provide 95 means for locking the shaft *a* against endwise movement such as effects unlocking, until the parts have been positioned so as expressly to provide for the endwise movement of the shaft. In this instance, the outer end of the pin or stud *b* is formed 100 with a hook by being bent as at *b'*, Fig. 3, so as to project back alongside the outer face of the collar *c* behind the rear wall of the notch *c'*. Through the engagement of this hook with the collar, at the outer side 105 of the latter, the required locking of the shaft against endwise movement outward is effected. The length of the hook is sufficient to allow the follower-projection 11^a to enter into a lease-groove 10^a and drop therein until it rests upon the bottom of the groove without the turning movement of the shaft *a* and collar *c* being sufficient to carry the back wall of the notch into a position clear 110 of the end of the hook *b'*. Thereby I prevent the means for locking the shaft from endwise movement from being unlocked through the dropping of the follower-projection into the lease-grooves from time to time prior to the final stoppage of the machine. When, however, the follower drops into the final stopping notch 10^b at the outer end of the scroll, the turning movement of the shaft and collar are sufficient to carry the back wall of the notch into a position clear 115 of the end of hook *b'*. Thereby, the shaft is unlocked and rendered free to be moved endwise by taking hold of its enlarged outer end *a*².

In case for any reason, it should be de-

sired to lift the follower at some intermediate point in its travel along the scroll, the necessary unlocking may be effected by first turning the pin or stud b so as to place the hook b' thereof in alinement with notch c' in collar c , thereby rendering the shaft a free to be moved endwise to disengage the collar from the pin, to render the shaft free to turn, as required for the raising of the follower from the scroll-groove.

The drawings show the follower equipped with an aliner h corresponding with that of the application aforesaid, for the purpose of keeping the follower in correct working relations with the proper turn of the scroll-spiral, and for preventing entry of the follower into the wrong turn of the scroll-spiral in passing from a lease-groove in the scroll. Such aliner is a blade that is pivoted at i , at one end thereof, to the follower-arm so that the aliner swings toward periphery of the scroll and under its edge enters the scroll-groove at a short distance from the follower-projection 11^a . By reason of the movable connection of the aliner with the follower, the aliner remains in the scroll-groove even though the follower be lifted sufficiently to withdraw the projection 11^a from the groove. Consequently, the return of the said projection to the particular turn of the scroll-groove from which it was lifted is ensured. The aliner prevents the follower from passing into the wrong turn of the groove in leaving a lease-groove, either as a result of the follower being pushed sidewise through carelessness on the part of the attendant in inserting the stick by which the follower-projection is held upraised in the lease-groove in first restarting after insertion of lease-threads or cords, or of the follower being jarred or shaken out of register with the turn, which it should enter.

As will be understood, unlocking of the shaft a by longitudinal movement of the same, rendering the said shaft and the follower free to be turned around the axis of the said shaft, as for the purpose of lifting the follower projection 11^a clear of the scroll, provides for any resetting of the follower at the points in the direction of the length of the scroll that may be necessary in operation. That is to say, in particular, provision is thereby made for enabling the follower, after the passage of the predetermined length of threads through the machine and the stoppage due to the dropping of the projection 11^a into the final stopping notch 10^b to be unlocked and moved back to the starting end of the scroll or to any proper point in the direction of the length of the scroll, in order there to be reengaged in the scroll-groove.

What is claimed as the invention is:

1. In a warper-clock or the like, in combination, a spirally-grooved rotating scroll,

a follower engaging with the groove or thread thereof, a shaft on which the follower is mounted with capacity to slide lengthwise thereof and with which it is engaged so that the two must turn in unison, and means for preventing the shaft and follower from turning so as to disengage the follower from the scroll, adapted to be locked and unlocked by relative movement of the interengaging elements in the direction of the length of said shaft.

2. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, and means for locking the shaft and follower to prevent disengagement of the follower from the scroll, adapted to be locked and unlocked by endwise movement of the shaft.

3. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, a fixed locking member, and a locking member carried by the shaft, the latter member adapted to be placed by endwise movement of the shaft in and out of locking engagement with the fixed member, and the locking engagement of said members serving to lock the shaft and follower to prevent disengagement of the follower from the scroll.

4. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, means for locking the shaft and follower to prevent disengagement of the follower from the scroll, adapted to be locked and unlocked by endwise movement of the shaft, and means for normally keeping the shaft in the position endwise in which it is locked from turning.

5. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, means for locking the shaft and follower to prevent disengagement of the follower from the scroll, adapted to be locked and unlocked by endwise movement of the shaft, and a spring normally keeping the

shaft in the position endwise thereof in which the locking means is operative.

6. In a warper-clock or the like, in combination, a spirally-grooved rotating scroll having a depression for indicating stoppage, a follower engaging with the groove or thread thereof and adapted to enter said depression, an endwise movable shaft on which the follower is mounted with capacity to slide lengthwise thereof and with which it is engaged so that the two must turn in unison, means for locking the shaft and follower to prevent disengagement of the follower from the scroll, adapted to be locked and unlocked by endwise movement of the shaft, and means for normally locking the shaft in locking position endwise, adapted to be unlocked by entry of the follower into the said depression of the scroll.
7. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, and means for locking the shaft to prevent the follower from being disengaged from the scroll, comprising a fixed locking member and an interengaging locking member carried by the shaft.

8. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, and means for locking the shaft to prevent the follower from being disengaged from the scroll, comprising a fixed locking stud or pin, and a member on said shaft having a notch that is entered by the stud or pin.

9. In a warper-clock or the like, in combination, a spirally-grooved rotating scroll having a depression for indicating purposes, a follower engaging with the groove or thread thereof and adapted to enter said depression, an endwise movable shaft on which the follower is mounted with capacity to slide lengthwise thereof and with which it is engaged so that the two must turn in unison, a notched collar on said shaft, and a fixed stud or pin normally occupying the notch of said collar and thereby locking the shaft and follower to prevent disengagement of the follower from the scroll but permitting the follower to enter the depression, and means in connection with said stud or pin for normally locking the shaft from endwise movement arranged to unlock it for such movement upon entry of the follower into the depression.

10. In a warper-clock or the like, in combination, a spirally-grooved rotating scroll, a follower engaging with the groove or thread thereof, an endwise movable shaft on which the follower is mounted with capacity to slide lengthwise thereof and with which it is engaged so that the two must turn in unison, a notched collar and a coacting stud or pin adapted to enter the notch of said collar, one of said elements fixed and the other attached to the shaft, adapted to coact to lock the shaft and follower against turning so as thereby to prevent disengagement of the follower from the scroll, and a spring acting to keep the shaft in its normal position endwise with the collar and the stud or pin in locking engagement with each other.

In testimony whereof I affix my signature in presence of two witnesses.

ARSENE SAULNIER.

Certificate of Correction.

It is hereby certified that in Letters Patent No. 1,437,865, granted December 5, 1922, upon the application of Arsene Saulnier, Waltham, Massachusetts, for an improvement in "Clocks for Warping Machines," errors appear in the printed specification requiring correction as follows: Page 1, line 18, for the misspelled word "terminated" read *termed*; line 22, for "enabling" read *enabling*; lines 53 and 54, for "induction" read *introduction*, and line 88, for the word "later" read *latter*; and that the said Letters Patent should be read with these corrections therein that the same may conform to the record of the case in the Patent Office.

Signed and sealed this 6th day of February, A. D., 1923.

[SEAL.]

KARL FENNING,
Acting Commissioner of Patents.
